UNITED STATES PATENT OFFICE.

CHARLES H. FRYE, OF BUFFALO, NEW YORK, ASSIGNOR TO HIMSELF AND
ARTHUR E. JEWELL, OF SAME PLACE.

DESIGN FOR A SUPPORT FOR MANTLES FOR GAS-BURNERS.

SPECIFICATION forming part of Design No. 30,902, dated May 30, 1899.

Application filed May 2, 1899. Serial No. 715,374. Term of patent 7 years.

To all whom it may concern:

Be it known that I, CHARLES H. FRYE, a citizen of the United States, residing at Buffalo, in the county of Erie and State of New York, have invented and produced a new and original Design in Supports for Mantles for Gas-Burners, of which the following is a specification, reference being had to the accompanying drawings, forming a part thereof, in which—

Figure 1 represents a perspective view of my improved support. Fig. 2 represents a side elevation of the same. Fig. 3 represents a top view of the support. Fig. 4 represents a bottom view of the support. Fig. 5 is a longitudinal section on or about line *a a*, Figs. 2, 3, and 4.

As shown in the accompanying drawings, the leading features of my design consist of the rod 1, having a cap 2 at its upper end and a plate 3 of woven-wire formation at its lower end. 20

Having described my invention, what I claim as new, and desire to secure by Letters Patent, is—

The design for support for mantles for gas-burners, as herein shown and described. 25

CHARLES H. FRYE.
